Patented Dec. 14, 1920.

UNITED STATES PATENT OFFICE.

THOMAS CLOUSTON, OF VANCOUVER, BRITISH COLUMBIA, CANADA.

GAS-PRODUCER.

1,362,559.

Specification of Letters Patent. Patented Dec. 14, 1920.

Application filed August 28, 1919. Serial No. 320,424.

To all whom it may concern:

Be it known that I, THOMAS CLOUSTON, a citizen of the Dominion of Canada, residing at Vancouver, in the Province of British Columbia, Canada, have invented certain new and useful Improvements in Gas-Producers, of which the following is a specification.

This invention relates to a gas generator for obtaining producer gas from powdered carbonaceous or from liquid fuel, such as crude oil, the generator being designed to give a continuous supply of producer gas with complete gasification of the fuel charge and without volatile constituents that require to be condensed before delivery of the gas for combustion. The gas is also in condition for use without scrubbing or other purifying treatment.

The invention is fully described in the following specification, reference being made to the drawings by which it is accompanied, in which:

Figure 1 is a vertical longitudinal section.

Fig. 2, a cross section on the line 2—2 in Fig. 1, and

Fig. 3, an end elevation of the generating chamber, being a section through the fuel delivery on the line 3—3 in Fig. 1, and Fig. 4 shows in cross section to a reduced scale a modification of the generator as for application to a furnace where there is consumption of the gas as generated, and

Fig. 5 shows a modification in the fuel delivery adapted for a liquid fuel such as crude oil.

In these drawings 2 represents an outer casing within which is sustained in an interspace 4 filled with broken refractory material a generating chamber 3 of similar refractory material.

This generating chamber 3 is preferably D-shaped in cross section disposed as shown in Fig. 2. It is closed at both ends and has vertical slits 5 along both sides.

Extending along the bottom of the combustion chamber 3 in the middle line from one end to a short distance from the other is an elongated cylindrical mixing chamber 6. This mixing chamber 6 is open at both ends and at one end passes through the end of the generating chamber. It may be integral with the generating chamber 3, but is preferably a separate part inserted through

the end of the chamber 3 and retained in position therein by any suitable means.

A gas uptake pipe 7 is connected to the outer casing 2 about the midlength of the chamber and delivers the gas as generated to the place of consumption or to a gas holder or storage reservoir.

To the end of the mixing chamber 6 which passes through the end of the generating chamber 3 is connected a relatively short chamber 8 forming an outward prolongation of the mixing chamber, within the end of which it conically projects, as at 9. Into the end of this chamber 8 is axially inserted a fuel delivery nozzle 10 to which finely divided carbonaceous fuel is delivered through a pipe 11 from a hopper 12 located above it. The lower end of the hopper delivers into the horizontally turned end of the pipe 11 in which is connected an air delivery pipe 13 having an outwardly flared end. The inner end of the air delivery pipe extends across the hopper delivery and is adjustable by a screw thread in its distance from the angle of slope of the powdered fuel to control the amount carried to the burner.

Delivering axially into the fuel delivery nozzle 10 and endwise adjustable in front of the fuel pipe 11 is a steam delivery nozzle 14 to which steam is delivered from a pipe 15 which passes lengthwise along the upper side of the combustion chamber and between it and the casing 2. Water is delivered to this pipe 15 from a reservoir 16, the supply being controlled by a stop valve 17 and a regulator 18 is introduced in the steam pipe between where it emerges from the casing 2 and its connection to the injector nozzle 14. This regulator 18 is controlled by a gas pressure governor 19 which is connected to the gas delivery pipe 7, so that the pressure of the gas as delivered controls the steam delivered to the generating chamber and thereby the fuel and air supply.

Resting saddle-wise on the upper side of the casing 2 is an air heating chamber 20, which in front of the gas uptake pipe 7 is medially divided along the top by a partition 21. To one side of this air heating chamber 20 external air is delivered at 22 and the opposite side is connected by a pipe 23 to the chamber 8. Closable cleaning apertures 24 are provided through the end of the retort

on each side in line with the bottom of the space between the mixing chamber 6 and the wall of the combustion chamber 3, through which apertures the flue dust may be removed periodically.

A removable cap 25 closes the end opposite the steam delivery nozzle 14, which cap may be removed to allow initial heating of the chamber 6 and ignition of the gases 10 therein, after which the jet of steam generated in the pipe 15 and delivered through the nozzle 14 into the mixing chamber 6 forms a partial vacuum in the fuel delivery pipe 11 which indraws the carbonaceous 15 fuel from the hopper 12 and the air from 13. This carbonaceous fuel and air is projected through the nozzle 9 into the mixing chamber 6, indrawing with it a supply of heated air from the chamber 20 through the 20 pipe 23.

The amount of air delivered with the carbonaceous fuel is carefully proportioned to be only sufficient to consume a portion of the fuel, and the heat of that combustion in the 25 presence of the unconsumed incandescent carbon is sufficient to dissociate the constituent gases of the steam by which it was injected, the oxygen of which is attracted to the incandescent carbon. The low 30 velocity of the gases at a relatively high temperature in their exit from the chamber 3 through the rubble filling 4 encourages contact of the CO_2 with the remaining particles of incandescent carbon, to form CO , which 35 with the free hydrogen constitutes the producer gas desired.

In the dissociation of the gases of the steam, heat is absorbed which is returned later when the free hydrogen is consumed. 40 This reduction of temperature is advantageous as it protects the combustion chamber from the destructive effect which the heat of complete combustion would have on the material of the chamber. 45 It must be distinctly understood that, although the arrangement shown is for the delivery of the carbonaceous fuel in the powdered form, the same construction of generator is applicable to the use of fuel 50 in a liquid form, such as crude oil, the only difference being in the manner of feeding the oil fuel to the burner.

Fig. 5 shows a modification of the fuel delivery to the burner adapted for a liquid fuel, such as crude oil. The oil is delivered by a pipe 30 through a needle valve 31 and a cap 32 located in the fuel delivery pipe 11 adjacent the burner 10, which cap is apertured at 33 to admit air. Depending 55 from this cap is a thimble shaped screen of wire gauze 34 within which one or more conical screens 35 are supported to spread the oil and divide it finely over the screen surface that it can be taken up by the air indrawn at 33 by the steam jet at 14.

The advantages of this process of gas generation are, that it is continuous and the constituents of the carbonaceous fuel are completely gasified, combining directly with the air and steam to form a producer gas 70 without any residue of condensable matter. These favorable results are attributable to the delivery of the fuel, whether solid or liquid, in a finely divided state, with a properly proportioned supply of air by means of a jet 75 of steam into an elongated chamber of relatively small cross section area and with an ample obstructed discharge delivery through the slits and rubble.

The total area of the slits 5 is approximately twice the cross section area of the mixing chamber 6, which is considerable in relation to that of the gas delivery pipe 7, so that the draft through the slits and 80 through the interspaces of the material in 85 is comparatively light, and the gases have time to effect the desired combination. The flue dust or ash resulting from the combustion of the powdered fuel is not therefore indrawn to the rubble to any large extent but is deposited within the combustion chamber 3 and is removable through the 90 cleaning apertures provided.

It is obvious that, if the casing 2 is open in the top, as shown in Fig. 4, the gas may 95 be consumed, as generated, if the air necessary for combustion is separately supplied as to a furnace.

Having now particularly described my invention, I hereby declare that what I claim 100 as new and desire to be protected in by Letters Patent, is:

1. A gas producer, comprising an elongated generating chamber of refractory material closed at both ends and having a number of 105 relatively small gas delivery apertures in its sides and a mixing chamber extending from one end to a short distance from the other, said generating chamber supported within a casing in a rubble of refractory material, 110 and means for delivering finely divided carbonaceous fuel with heated air and steam axially into one end of the mixing chamber.

2. A gas producer, comprising an elongated generating chamber of refractory material having gas delivery apertures in its walls and a mixing chamber extending lengthwise from one end to a short distance from the other, a casing wall retaining a filling of broken refractory material in close 120 contact with the top, bottom and sides of the generator, and means for delivering finely divided carbonaceous fuel with air and steam axially into one end of the mixing chamber.

3. A gas producer, comprising an elongated generating chamber of refractory material having apertured walls and within it a mixing chamber extending from one end of the generating chamber to a short distance from the other end, said generating chamber 125 130

supported within an external casing with a rubble filling of refractory material in the space between the generator and the casing, means for delivering finely divided carbonaceous fuel with heated air and a jet of steam axially into one end of the mixing chamber, and means for withdrawing the gas from the external casing.

4. A gas producer, comprising the combination with an elongated generating chamber with means for delivering gas therefrom through a rubble of refractory material surrounding the generator, a burner projected axially into the mixing chamber, said burner comprising a nozzle to which a supply of heated air is delivered, a second nozzle projected from the back toward the air nozzle to which second nozzle finely divided carbonaceous fuel is delivered, and a third nozzle delivering a jet of steam axially through the two first named nozzles, the relative position of the nozzles and their cross section areas being such that the jet of steam will in draw the finely divided fuel and the heated air and will deliver them axially through the burner.

5. A gas producer, comprising an elongated chamber of refractory material D-shaped in cross section having vertically disposed slits along each side, and a mixing chamber lengthwise disposed along the bottom or flat side from one end to a short distance from the other, an external casing retaining a rubble of refractory material in contact with the walls of the generator, air ducts supported above the casing through which air is delivered to a burner projected axially within the mixing chamber, a fuel delivery nozzle projected into the back end of the burner, means for delivering finely divided carbonaceous fuel to the fuel nozzle, a steam jet projected into the back end of the fuel nozzle, a pipe disposed lengthwise over the generator within the casing, means for

delivering a regulated supply of water to one end of this pipe the other end of which is connected to the steam delivery nozzle.

6. A gas producer, comprising an elongated chamber of refractory material having gas delivery slits disposed along each side, and a mixing chamber lengthwise disposed along the bottom from one end to a short distance from the other, an external casing retaining a rubble of refractory material in contact with the walls of the generator, said chamber having a gas delivery duct from it, means for projecting a jet of finely divided carbonaceous fuel with air and steam into the end of the mixing chamber, means for heating the air before such delivery, and means co-operative with the pressure of the gas as delivered from the generator for controlling the amount of steam delivered to the burner.

7. A gas producer, comprising an elongated chamber of refractory material D-shaped in cross section, the flat side of the D being horizontally disposed, the side walls of the chamber adjacent the flat side having vertically disposed narrow slits, a cylindrical mixing chamber lengthwise disposed along the bottom within the generating chamber from one end to a short distance from the other, a casing retaining a rubble of refractory material in contact with the wall of the generating chamber, a burner nozzle projecting axially into one end of the mixing chamber, means for delivering heated air to the burner, a fuel delivery nozzle projecting axially from the back end toward the burner nozzle, means for delivering finely divided carbonaceous fuel and air to the fuel nozzle, and a steam nozzle projecting axially from the back end toward the fuel nozzle, and means for delivering steam to the last mentioned nozzle.

In testimony whereof I affix my signature.
THOMAS CLOUSTON.
